AUTOMATIC LEVELING MECHANISM FOR HYDRAULIC MOTORS, ELEVATORS, ETC.

John A. Rogers, Rockville Centre, N. Y., assignor to Hydraulic Elevator & Machine Company, Brooklyn, N. Y., a corporation of New York

Application July 8, 1932, Serial No. 621,504

7 Claims. (Cl. 187—28)

This invention relates to automatic leveling mechanism for hydraulic motors, elevators, etc., and has particular reference to means whereby a hydraulic motor, and more particularly a direct hydraulic plunger elevator can be held automatically at a floor level, when the control lever is at neutral position.

The invention is described herein in connection with the elevator mechanism shown in patent to Larsson #786,654, April 4, 1905, to which reference is made for a detailed description of plunger elevator, main and pilot valve, controlling mechanism, etc.

A system in general consists of a cylinder set vertically in the ground to a depth equal to the rise of the elevator, the car being carried by a plunger reciprocating vertically in the cylinder, and the car partly counter balanced by counter-weights connected to the car by cables running over overhead sheaves, the varying buoyancy of the plunger being compensated for by varying weight of counter-weight cables on one or the other side of the system. Admission of water under pressure to the cylinder through a supply valve lifts the car, and exhausted water from the cylinder through an exhaust valve, lowers the car. The main supply and exhaust valves are motor operated and are connected to the cylinder by a to-and-from pipe. To control the actuating motor or motors actuating the main exhaust and supply valve is a pilot valve, which in turn is connected by cables to the lever in the car which is under the control of the operator. Usually there is a linkage between the pilot valve and the main valve, so that the pilot valve is automatically closed when the main valve is at rest in either open or closed position, and the degree of opening of the pilot valve to start or stop the car correspondingly controls the degree of opening or closing of the main valve to start or stop the car, or control the speed of the car.

In an experience of over thirty years' successful operation of these elevators for high rises and at high speeds, need has been felt for some auxiliary control system whereby the car could be automatically leveled at the floor without so many manipulations of the car control lever, and also for a device to prevent uncontrolled rise or fall of the car when stopped at a floor with the control lever in neutral position, such rise or fall being due to leakage through the valves. It is impossible to maintain the packings of such valves so tight as to have no leakage, and leakage of supply pressure through the valve to the cylinder will raise the car, whereas more common

leakage of water from the cylinder through the exhaust causes the car to drop away from the floor, even though the car control lever is at neutral and the operator thinks the car will hold stationary. Accidents have been known to happen to operators leaving the car at a floor and falling down the hatchway because not observing that the car had crept away from the floor. So far as I am aware, no device has heretofore been proposed for successfully meeting these conditions.

According to this invention, I provide an auxiliary supply and exhaust valves connected to the to-and-from pipe and automatically control these valves by means disposed in the hatchway at the one or more floors where it is desired to automatically level the car. If the car tends to drop away from the floor, it, through the hatchway connections, will open the auxiliary supply valve and admit pressure to the cylinder, and if it tends to rise from the floor as by leakage of supply pressure into the cylinder, a similar device will open the auxiliary exhaust valve and let the excess pressure out of the cylinder. While either may be used alone, it is preferable to use both as thereby, with proper spacing of the hatchway devices at the floor or floors, the elevator can only move a slight distance from resting position without bringing itself back.

The hatchway devices are actuated by a withdrawable connection to the car control lever, which itself works in conjunction with a quadrant fastened to the car having a central notch into which a latch or bolt drops when released by the hand of the operator. At this position the actuating device is extended to cooperate with the hatchway devices, but at any running position, the latter are inoperative owing to withdrawal of the actuating device.

A particularly novel detail of the invention resides in a linkage means to withdraw the actuating device, which, when straightened at the neutral position of the car lever, acts as a thrust element from the hatchway devices back to the car lever pivot, without back thrust on the lever. Thus the leveling device functions when the car lever is in neutral position, without requiring any attention by the operator. A further novel detail of the invention resides in the adjustments permitted for the hatchway devices to insure the desired timing, and also to means whereby the auxiliary or leveling supply and exhaust valves are self closing or normally closed except when one or the other is opened by the hatchway device.

Referring to the accompanying drawings, Fig. 1 is a partial elevation of a system embodying the invention.

Fig. 2 is a detail of a hatchway and car controlling device.

Fig. 3 is a detail of the auxiliary supply and exhaust valves and piping.

1 represents a cylinder, 2 the plunger carrying the car 3, 4 the floor, 5 the main valve connected to pressure supply 6 to exhaust 7, 8 the pilot valve controlled by lever 9 connected by standing ropes 10 to the car lever 11 pivoted on a car floor at 12, and carrying pulleys 13 over which the standing ropes 10 run in usual manner. 14 are automatic end stop valves which need not be described; and 15 is the to-and-from pipe connected at the top of cylinder 1. 16 is the notch in the car quadrant receiving spring actuated bolt 17 on the car lever, which bolt is drawn against the spring by the hand of the operator and when he lets go, either rides on the quadrant or drops into the notch 16 when the car lever is put into neutral position.

Describing first the auxiliary supply side for bringing the car back to the floor when it has dropped below, 20 represents a pressure pipe tapped from supply 6 and connected to valve casing 21 containing a reciprocating ported plug valve 22 (see Fig. 3). This supply pressure passes from valve casing 21 through pipe 23 to an auxiliary to-and-from pipe 24 connected to main to-and-from pipe 15. To stem 25 of valve 22 is connected a link 26 which in turn is connected to lever 27 pivoted at 28 carrying a weight 29. To end of lever 27 is a flexible connection such as chain 30 running over pulleys 31, 32, and connected to a preferably flat steel tape 33 extending up the hatchway and suspended at the top of the building by a weight running over a pulley, or a spring to counter-balance them and hold them under proper tension, it being seen that when the steel tape is lifted by means hereafter to be described, the valve 22 will be opened to admit auxiliary supply pressure from pipes 6, 20, 23, 24 to the cylinder 1 to lift the plunger 2 and restore the car to the floor level.

A similar mechanism is provided for the exhaust side comprising exhaust pipe 36, exhaust valve casing 37, exhaust valve 38, exhaust pipe 39 leading to auxiliary to-and-from pipe 24. Also, link 40, lever 41, weight 42, chain 43, running over pulleys 44, 45 connected to a second flat steel tape 46 extending up the hatchway parallel to tape 33 and suspended at the top of the building by a weight running over a pulley, or a spring to counter-balance them and hold them under proper tension, are provided for actuating the auxiliary exhaust valve.

48 is a non-return check valve in supply pipe 60 23, and 49 is a similar valve in exhaust pipe 39. 50, 51 are independently adjustable set cocks for controlling the rate of flow in the respective supply and exhaust pipes 23, 39, to determine the speed of returning the car to level position.

65 The valves 22, 38 are similarly constructed, being externally cylindrical and internally hollowed on a taper as shown, with sets of ports 52, 53, 54 therein, for passing the water through the valve casing when lifted. The function of the internal taper is to permit an unbalanced component of the pressure to seat the valve, and in effect aid the weights 29, 42, it being essential that these valves 22, 38 be normally seated and yet be so constructed as to not require too much actuating pressure to overcome the static unbalance and

the weights. These cylindrical valve stems 22, 38 are packed by the usual external hat packings, with usual stuffing boxes at the top.

Referring to Fig. 2, at each floor in the hatchway adjacent the travel of the car, or at certain floors where automatic leveling is desired are mounted on pivots 54, one or two cams 55, 56. These cams are mounted on a parallel linkage as shown, and when pressed outwardly of the car, or to the left in Fig. 2, lift their respective steel tape 33 or 46. This is effected by blocks 57, 58 mounted on tapes 33, 46 respectively, so that when the cams 55 or 56 are pushed in, as by rollers 60 on the car, the levers 61, 62 are lifted and in engaging blocks 57, 58, lift the respective tape 33 or 46 and thereby open the corresponding auxiliary supply or exhaust valve. The blocks 57, 58 are clamped on the tapes by bolts, and can be adjusted up and down to fit. Springs 63, 68, return the cams 55, 56 to normal position. Set screws 64, 64 are provided for adjusting the inward positions of cams 55, 56.

Passing now to the car mechanism, roller 60 before mentioned, is mounted on block 67 sliding on a suitable trackway 68 beneath the car, and block 67 is connected by rod 68 to a second similarly mounted block 69. To block 69 is pivoted a link 70 which latter is pivoted to arm 71 rigidly mounted on controller lever shaft 12. The link 70 and arm 71 constitute a linkage, when straightened out at the time the car control lever is in neutral position, forms a thrust mechanism to project the roller 60 into the path of the cams. This is some seconds before the car actually stops, because time is required after the operator brings the car lever to center and opens the pilot valve to close the main valve for the main valve to close, and in doing so, automatically close the pilot valve. If the car stops at the desired level, then roller 60 comes to rest 40 between cams 55, 56. If the car stops too soon, being below the floor, then the roller 60 through cam 55 and block 57 lifts tape 33 and opens auxiliary supply valve 22. Likewise, if the car has once stopped at the floor and sinks because of 45 leakage, then cam 55 is pushed outwardly by roller 60 and admits sufficient supply to bring the car back to the floor. A slight space will ordinarily be left between cams 55, 56 to receive rollers 60 in order to prevent tendency to teetering. If the car stops above the floor, then the roller 60 has pushed cam 56 outwardly, which operates similarly to open exhaust valve 38 and let the car down, or if there is leakage through the supply side of the main valve tending to 55 raise the car, then this leakage is exhausted and the car brought back to level.

As will be seen, the arm 71, being longer than link 70 tends to quickly withdraw roller 60 from between the cams. When the linkage is straightened out and the roller 60 projected to contact with the cams 55 or 56, there is no back thrust against the operator on the control lever.

By this invention a new and useful improvement is made applicable to hydraulic elevators which will not only increase their efficiency by eliminating excess motions in stopping at a floor, but by saving excess use of pressure water, saves power in the pumping plant. Also, this mechanism will detect leakage which is ordinarily neglected, by causing the elevator to move slightly back and forth when it is supposed to be at rest, but inasmuch as it prevents creeping in either direction, provides an additional safeguard.

While the valves and details shown herein are 75

preferred, it is to be understood that the invention is applicable to hydraulic motors used for various purposes where creeping due to leakage is undesired, and to hydraulic elevators of various types and with various kinds of valves, and I do not restrict myself to the details shown herein except as specifically required by the appended claims.

I claim:

1. A hydraulic elevator controlling apparatus comprising a pivoted control lever, an arm carried thereby, a link pivoted to said arm, a sliding member attached to said link and mounted to slide in a line including the link attachment and normal to the control lever axis, and actuating member carried by said sliding member, hatchway means adjacent a floor operated by said actuating member when projected, and motor control means connected to be actuated by said hatchway means.
2. In a hydraulic elevator controlling apparatus, hydraulic motive means for moving the car, a control member movable to one position to render said motive means inoperative and to another position to render said motive means operative to move the car, a projectable actuating member carried by the car and connected with said control member to be moved thereby, control means adjacent a floor engaged and operated by said actuating member when the latter is projected, said control member moving said actuating member to projected position when said control member is in its inoperative position, the projection of said actuating member resulting in an arrangement of parts so that there will be no force transmitted to the control member in a direction tending to move the same when the actuating member engages said control means.
3. In a hydraulic elevator controlling apparatus, hydraulic motive means for moving the car, a control member movable to one position to render said motive means inoperative and to another position to render said motive means operative to move the car, a projectable actuating member carried by the car and connected with said control member to be moved thereby, control means adjacent a floor engaged and operated by said actuating member when the latter is projected, said control member moving said actuating member to projected position when said control member is in its inoperative position, means between said control member and said actuating member and operative when the control member is in inoperative position to lock the actuating member in its projected position, said locking means being released by movement of said control member towards operative position.
4. In a hydraulic elevator controlling appara-

tus an operator's pivoted control member, a projectable actuating member carried by the car connected with said control member to be actuated thereby, motor control means adjacent a floor operated by said actuating member when the latter is projected, the projection of said actuating member resulting in an arrangement of the parts so that there will be no turning moment transmitted to the control member when the actuating member engages said motor control means.

5. In a hydraulic elevator controlling apparatus wherein there is provided an operator's controller comprising a rotary member, a projectable actuating member slidably carried by the car, and connecting means between said rotary member and the said actuating member, motor control means adjacent a floor operated by said actuating member when the latter is projected, the projection of the said actuating member resulting in an arrangement of the parts so that there will be no turning moment transmitted to the controller when the actuating member engages said motor control means.

6. In an elevator system, the combination with a car, of hydraulic motive means for running said car including a main valve, controlling means for said hydraulic motive means and including an operator's pivoted control element in the car which is in neutral position when the main valve is closed, automatic means effective when said control element is in neutral position for leveling the car, said automatic means including motor control means adjacent a floor, a projectable actuating member connected with said control element to be projected into a position to engage said control means when the control element is in neutral position, the projection of said actuating member resulting in an arrangement of the parts so that there will be no turning moment transmitted to the control member when the actuating member engages said motor control means.

7. Means for automatically holding a hydraulic elevator level at a floor against creeping when the main valve is shut, comprising auxiliary controlling means, means in the hatchway adjacent a floor level connected to said controlling means, a pivoted control element in the car, and means on the car arranged to be projected by said control element into a position to engage said hatchway means to actuate said hatchway means when the car creeps to cause said controlling means to reverse the car, the projection of said projectable means resulting in an arrangement of the parts so that no turning moment will be transmitted to the control element when the projectable means engages said hatchway means upon creeping of the car.

JOHN A. ROGERS. 60
